CLAIM

We claim the ornamental design for a computer, as shown and described.

DESCRIPTION

FIG. 1 is a front perspective view of the claimed design; FIG. 2 is a top plan view thereof; FIG. 3 is a bottom plan view thereof; FIG. 4 is a right side elevational view thereof; FIG. 5 is a left side elevational view thereof; FIG. 6 is a front elevational view thereof; and, FIG. 7 is a rear elevational view thereof.

The broken lines in the drawings are directed to environmental structure and are for illustrative purposes only. Accordingly, the broken lines form no part of the claimed design.

1 Claim, 5 Drawing Sheets
